UNITED STATES PATENT OFFICE.

ROBT. R. TAYLOR, OF READING, PENNSYLVANIA.

APPARATUS FOR VENTILATING RAILROAD-CARS.

Specification of Letters Patent No. 23,049, dated February 22, 1859.

To all whom it may concern:

Be it known that I, ROBERT R. TAYLOR, of Reading, Berks county, State of Pennsylvania, have invented certain new and useful Improvements in Apparatus for Ventilating Railroad-Cars; and I do hereby declare the following to be a full, clear, and exact description of the same, reference being had to the accompanying drawing and 10 to the letters of reference marked thereon.

My invention relates to an improvement in apparatus for forcing a constant supply of air into railway cars; and my improvement consists in a blowing cylinder, hung to 15 one of the trucks of the car, and operated from one of the axles by means of an eccentric or an equivalent device, in combination with flexible or self-accommodating pipes for admitting air to and discharging 20 it from the cylinder, and with distributing pipes for admitting the compressed air to the car, the whole being arranged substantially as described hereafter.

In order to enable others to make and use 25 my invention, I will now proceed to describe its construction and operation.

On reference to the accompanying drawing, which forms a part of this specification; Figure 1 is a longitudinal section of a railroad car, showing my improved apparatus 30 for ventilating the same; Fig. 2, an inverted plan.

The body A of the car, the trucks B, and 35 wheels C with their axles and boxes, are similar and are arranged in a similar manner, to those of ordinary railroad cars. To one of the axles an eccentric D is secured, which is embraced by a strap E, the latter being rigidly connected to the piston rod F 40 of the blowing cylinder G. On each side of this cylinder is a chamber, that on one side communicating with a hollow trunnion a, and that on the opposite side with a hollow trunnion a'. These trunnions are hung to 45 brackets d and d', which are permanently secured to one of the beams of one of the trucks. An elastic pipe H, of leather, gutta percha or gum elastic, is attached to the end of the trunnion a, and extends into a cistern 50 J, which contains a supply of water. Another pipe I is attached to the opposite trunnion a', and passes along the under side of the car and upward either through or outside the latter, so as to terminate above the 55 roof. The chambers on the opposite sides of the cylinder are each furnished with two

valves one at each end, the chamber communicating with the hollow trunnion a having its valves opening outward from the cylinder, and the chamber communicating with the hollow trunnion a' having its valves arranged to open inward, after the manner common to ordinary blowing cylinders, and too well known to need a more minute description. Pipes K and K', communicating 60 with the cistern or chamber J, extend along the under side of the car, and, attached to these pipes, are a series of small branches communicating with the interior of the car. 65

On each side and near the roof of the car are a series of openings M, in which are hung to suitable cross-bars a series of vaned 70 wheels, the vanes projecting a short distance through the openings on the outside of the car.

As the car is drawn over the track, a reciprocating motion will be imparted to the piston within the cylinder G by the eccentric D and rod F, the cylinder vibrating in the brackets d and d', and thus accommodating itself to the different angles assumed by the rod, after the manner of ordinary vibrating engines. A continuous blast of air will thus be forced, through the trunnion a and elastic pipe H, into the reservoir J, while the cylinder is furnished with a constant supply of air through the pipe I and trunnion a'. The pipe H is made of flexible material, in order that it may 80 move and accommodate itself to the motion of the cylinder, as well as to that of the truck, without interrupting the passage of the air. For a similar reason, the lower end of the suction pipe I is also made elastic, the perpendicular portion being rigid, and passing through the roof of the car, so that the air drawn into the cylinder may be as 85 free from dust and other impurities as possible. Should the air drawn into the cylinder become impregnated with any particles of dust, it is deprived of the same by contact with the water in the reservoir J, so that the air which passes along the pipes K and K' and through their branches into the car is perfectly free from all 90 impurities. Simultaneously with the injection of a constant supply of pure air into the interior of the car, the projecting portion of the vane wheels in the openings M are turned around by the impulse of the external air, caused by the progress of the car, and the rapid revolving motion of the vanes 95 100 105 110

tends to facilitate the escape of the impure air from the interior of the car, to make way for the pure air forced into it by the blowing cylinder. It will be seen, without further description, that as the car moves a thorough ventilation of the interior will be effected.

I do not claim broadly, the forcing of air into railway cars by a blowing apparatus 10 operated by the axles, as such a device is described in the patents of R. Cook, Aug. 19th, 1851, and J. H. Taylor, Oct. 30th, 1855; nor do I claim an air pump or air pumps operated by the axles, as they have 15 been heretofore used in connection with pneumatic car springs. I also disclaim the rotating, ventilating valves M, the same or their equivalents having been heretofore used; but

I claim and desire to secure by Letters 20 Patent;

The blowing cylinder G, hung to one of the trucks of the car, and operated from one of the axles by means of an eccentric D or other equivalent device, in combination with 25 the flexible or self-accommodating inlet and discharge pipes I and H and the distributing pipes K, the whole being arranged substantially as and for the purpose herein set forth.

In testimony whereof, I have signed my name to this specification in the presence of two subscribing witnesses.

R. R. TAYLOR.
